United States Patent [19]

Nozaki

[11] Patent Number: Des. 360,728

[45] Date of Patent: ** Jul. 25, 1995

[54] **RAIL FOR A LINEAR MOTOR DRIVEN CONVEYANCE DEVICE FOR CONVEYING SMALL THINGS**

4,520,733 6/1985 Willmann 104/93
4,531,460 7/1985 Pamer 104/107
4,733,615 3/1988 Volkstorf 104/93

[75] Inventor: **Takashi Nozaki**, Ise, Japan

Primary Examiner—Susan J. Lucas

[73] Assignee: **Shinko Electric Co., Ltd.**, Tokyo, Japan

Assistant Examiner—Robin V. Taylor

Attorney, Agent, or Firm—Thompson, Hine & Flory

[**] Term: **14 Years**

CLAIM

[21] Appl. No.: **19,129**

The ornamental design for a rail for a linear motor driven conveyance device for conveying small things, as shown and described.

[22] Filed: **Feb. 23, 1994**

DESCRIPTION

[30] Foreign Application Priority Data

Aug. 27, 1993 [JP] Japan 5-26172
[52] U.S. Cl. **D34/29; D25/119**
[58] Field of Search D34/29, 28; 104/93,
104/106, 107; 105/150; 198/619

FIG. 1 is a perspective view of a rail for a linear motor driven conveyance device for conveying small things showing my new design;

FIG. 2 is a front elevational view thereof;

FIG. 3 is a rear elevation view thereof;

FIG. 4 is a top plan view thereof;

FIG. 5 is a bottom view thereof;

FIG. 6 is a left side elevational view thereof, the right side being a mirror image; and,

FIG. 7 is a cross-sectional view taken along line 7—7 in FIG. 2.

The rail in FIGS. 1—5 is shown broken away to indicate indeterminate length.
